STOCKING PROTECTOR

Harry R. Taylor, Portland, Oreg., assignor of one-half to Buford V. Bridgewater, Portland, Oreg.

Application November 23, 1937, Serial No. 176,064

2 Claims. (Cl. 36—70)

This invention relates generally to foot wear and particularly to a stocking protector.

The main object of this invention is the construction of an exceedingly simple and efficient 5 form of stocking protector adapted to be inserted in a shoe around its upper margin for the purpose of protecting the stocking while the shoe is being polished.

The second object is the construction of a device of the class described which will be economical to manufacture, easy to insert in the 10 shoe and easy to remove therefrom.

The third object is to construct a device of the 15 class described which will lend itself to use as an advertising medium.

I accomplish these and other objects in the manner set forth in the following specification as illustrated in the accompanying drawing, in which:

20 Fig. 1 is a plan of the preferred form of the device.

Fig. 2 is a side elevation thereof.

Fig. 3 is a perspective view showing the device used in an ordinary form of oxford.

25 Fig. 4 is a perspective view showing the device used in connection with what is known as the tie-shoe.

Fig. 5 is a plan of an accessory used in connection with the tie-shoe.

30 Fig. 6 is a perspective view of the device itself formed in a wearing position.

Similar numerals refer to similar parts throughout the several views.

Referring in detail to the drawing, there is 35 shown a V-shaped body member 10 of cardboard or other suitable material having the convex outer corner 11 and a concave inner corner 12. Radial slots 13 may be formed near the ends of the curved portion 11 to facilitate fitting the device to the foot of the wearer. The ends 14 may be squared as shown or rounded.

In Fig. 5 is shown a tongue 15 which is used in conjunction with the body member 10 when tie-shoes are being polished. When the ordinary oxford 17 is being polished the body member 10 alone is sufficient.

5 The operation of the device is as follows:

Before commencing the polishing of a shoe, while it is being worn, the shoe black first slips the body member 10 into position shown in Fig. 3 or if a tie-shoe 16 is worn, he first inserts the 10 tongue 15 as shown in Fig. 4 and then proceeds with the polishing operation.

It will be noted that the upper edge 18 of the body 10 is kept above the upper edge 19 of the shoe 16 or 17 leaving a sufficient protecting area 15 which will prevent the stocking 20 from becoming soiled.

It must be understood that the exact details of this device may be varied to suit the style of shoe as well as its size and that the type of material employed therein may also vary according to the requirements without departing from the spirit of this invention.

20 I claim:

1. A stocking protector of the class described 25 consisting of a strip of flat flexible material having two elongated ends normal to each other and characterized by having the junction of said ends curved in the manner that the shapes of the inner and outer edges thereof are substantially 30 identical.

2. A stocking protector of the class described 35 consisting when completed of a strip of flat flexible material the opposite ends of which are normal to each other and the intermediate portion 35 of which is curved in a manner to join said ends with a rounded corner whereby the inner and outer edges of said strip are substantially identical in shape.

HARRY R. TAYLOR. 40
